UNITED STATES PATENT OFFICE.

CHARLES DAVID BONSALL, OF PARNASSUS, PENNSYLVANIA, ASSIGNOR, BY MESNE ASSIGNMENTS, TO P. H. MURPHY COMPANY, OF PARNASSUS, PENNSYLVANIA, A CORPORATION OF PENNSYLVANIA.

CAR ROOF.

Application filed October 2, 1920. Serial No. 414,302.

To all whom it may concern:

Be it known that I, CHARLES DAVID BONSALL, a citizen of the United States, and a resident of the city of Parnassus, in the county of Westmoreland and State of Pennsylvania, have invented a new and useful Improvement in Car Roofs, of which the following is a specification.

This invention relates principally to car roofs of the all steel riveted type, wherein heavy gage self-supporting roof sheets extend from side to side of the car, the roof sheets being rigidly secured together along their side margins and their eaves portions being rigidly secured to the side plates of the car.

One of the principal objects of the present invention is to provide a roof consisting solely of roof sheets, thereby dispensing with separate inside and outside carlines, and seam covers which heretofore have commonly been used in the above type of roof. Another object is to produce a strong and durable roof of simple construction which can be cheaply manufactured and easily assembled and which will permit the use of sheets of lighter gage than those heretofore required for roofs of the all-steel riveted type, thereby reducing the weight and cost of the roof and, at the same time, greatly increasing the strength of the roof. Another object is to produce a roof comprising parallel upper and lower surfaces extending cross-wise of the car, offset alternately with respect to each other and connected by substantially vertical web portions, whereby an even distribution of the metal above and below the horizontal center line of the roof is obtained, thus placing the neutral axis of the roof along said center line and thereby enabling the maximum strength of the metal to be utilized.

The invention consists principally in a car roof comprising a plurality of self-supporting roof sheets, so formed that, when assembled with their side margins rigidly secured together, the sheets form a roof having parallel upper and lower surfaces of equal area extending transversely of the car and alternately offset with respect to each other and connected by substantially vertical web portions, thus forming a series of flat topped ribs extending crosswise of

the car and alternating with flat bottomed channels, thereby locating the neutral axis of the roof midway between the plane of said ribs and the plane of the bottoms of said channels and enabling the maximum strength of the metal to be obtained. The invention further consists in the combinations and arrangements of parts hereinafter described and claimed.

In the accompanying drawings, which form part of this specification, and wherein like symbols refer to like parts wherever they occur—

Fig. 1 is a top plan view of the end portion of a car roof embodying my invention;

Fig. 2 is an end elevation of the same, drawn to a slightly larger scale;

Fig. 3 is a longitudinal cross-section through the ridge portion of the roof at the end of the car, the section being taken on the line 3—3 in Fig. 1;

Fig. 4 is an enlarged detail longitudinal cross-section taken through the roof between the ridge and the eaves, the section being taken on the line 4—4 in Fig. 1;

Fig. 5 is a detail longitudinal cross-section through the roof at the eaves, the section being taken through the upper flange of the side plate on the line 5—5 in Fig. 1;

Fig. 6 is a transverse cross-section through the eaves portion of the roof looking in the direction of one of the roof joints, the section being taken on the line 6—6 in Fig. 1;

Fig. 7 is a longitudinal section taken through the end portion of the roof between the eaves and the ridge on the line 7—7 in Fig. 1;

Fig. 8 is a perspective view of the eaves portion of one of the roof sheets;

Fig. 9 is a fragmentary plan view of a car roof showing roof sheets of modified form;

Fig. 10 is an enlarged transverse cross-section through the same on the line 10—10 in Fig. 9; and

Figs. 11, 12, 13, 14, 15 and 16 are longitudinal cross-sections similar to Fig. 4, showing roof sheets of modified form.

The roof shown in Figs. 1 to 8 of the drawings is applied to a steel box car having a roof substructure comprising metal angle-bar side plates 20, which are arranged with one flange up and facing outwardly. A steel car end 21, whose upper portion is

flanged inwardly, as at 22, and is inclined downwardly on opposite sides of the ridge to conform to the pitch of the roof, has its upper portion connected to the end of the angle-bar side plates in any desired manner. The flange 22 is made wider at the eaves than at the ridge to strengthen the end of the car against horizontal stresses, and an angle-bar end plate 23, which slopes downwardly on opposite sides of the ridge with the outwardly projecting top flange thereof flush with the top flange 22 of the end plate, has its vertical flange secured to the upper portion of the car end by means of rivets 24. The horizontal flange of the end plate angle 23 is disposed uppermost and projects outwardly from the car end flush with the inwardly projecting flange 22 thereof.

Transversely arranged load sustaining roof sheets 25 span the car from side plate to side plate with their eaves portions supported on the upper flanges thereof. The roof sheets slope downwardly on opposite sides of the ridges to form a pitch (or ar- cuate) roof and are formed with parallel upper and lower surfaces 26 and 27, which extend crosswise of the car and are of a width corresponding to half the width of the sheets. The adjacent inner marginal portions of the vertically offset surfaces 26 and 27 are connected along the middle of the sheets by substantially vertical web portions 28.

The upper surface 26 of each sheet is provided along its outer margin with a depending flange 29, whose lower edge terminates a short distance above the plane of the lower surface 27 thereof; and said lower surface is provided along its outer side margin with an upstanding flange 30, whose upper edge terminates a short distance below the plane of the upper surface of the sheet. Thus, one-half of each sheet is formed with a flat topped rib or inverted channel portion 31 and the other half of the sheet is formed with a flat bottomed upwardly opening channel 32, both channel and rib extending crosswise of the car. The sheets are assembled by lapping the depending outer flange 29 of the rib or downwardly opening channel 31 of a sheet over the upstanding flange 30 of the upwardly opening channel 32 of the next adjacent sheet and securing said flanges together, throughout their length, midway between the upper and lower surfaces 26 and 27 by rivets 33. Thus, when assembled, the sheets form a single course roof having a series of flat topped ribs extending crosswise of the car alternately with flat bottomed channels. The web portion 28 that connects the upper surface 26, which forms the top of the rib 31, with the lower surface 27, which forms the bottom of the channel 32, forms the inner side wall of said rib and channel; and the depending flange

29 and the upstanding flange 30 form the outer side wall of said rib and said channel. The lower surface 27, which forms the bottom portion of the channel 32 of each sheet, rests upon the upper flange of the side plates 70 and is rigidly secured thereto by means of rivets 37. The eaves ends of the upstanding underlapping flanges 30 of the sheets are flattened out over the top flange of the side plate in the plane of the lower surfaces 27, 75 as at 34. The eaves ends of the sheets are bent down over the outer edges of the top flanges of the side plates, forming drip flanges 35.

The upper surfaces 26, which form the tops of the downwardly opening channel or ribs 31 of the sheets, are curved downwardly near the eaves ends of the sheets and merge into the plane of the lower surfaces 27, which form the bottom of the upwardly 80 opening channels 32, at the point where the depending flanges 35 are turned downwardly. The depending outer side flange 29 of each rib or inverted channel 31, together with the surplus metal gained by the merging of the top portion 26 of the said rib into the plane of the bottom portion 27 of the upwardly opening channel 32, is turned outwardly over the bottom portion 90 of the upwardly opening channel 32 of the next adjacent sheet in the form of a laterally extending flange 36, which flange, together with the underlying bottom portion 95 of channel 27 of the next adjacent sheet, is rigidly secured to the upper flange of the side-plate by means of the rivet 37.

Running boards 39 rest on and are secured to the top flanges of angle for running board saddles 40 which have their vertical flanges arranged flatwise against the depending 105 outer flanges 29 of the ribs 31 and are secured in position by means of the rivets 33 which secure together the lapped flanges 29 and 30 of adjacent sheets.

The end sheets 42 are each provided with 110 an upstanding flange 43 along their inner margins, which extends upwardly into the rib 31 of the adjacent sheet, alongside of the depending flange 29 at the outer margin thereof, and is secured thereto by a row of 115 rivets 44. The body portion of the end sheet is in the plane of the bottoms 27 of the upwardly opening channels of the main sheets 25 and rests on and is secured to the outwardly projecting flange of the end angle 23 by rivets 45. The outer margin of the end sheet is turned down over the outer edge of the top flange angle 23 in the form of a drip flange 46.

The running boards 39 project beyond the 125 end of the car and have an angle iron 47 extending crosswise thereof, the horizontal flange of which is bolted or otherwise secured to the undersides of the running boards. The overhanging ends of the run- 130

ning boards are braced and supported from the steel end 21 by means of inclined strap braces 48, which have their upper and lower ends riveted or otherwise secured to the vertical flange of the angle 47 and car end 21 respectively.

The hereinbefore described sheets, when assembled form a roof having flat portions of equal area extending cross-wise thereof 10 that are offset alternately up and down so that the flat portions lie at one or the other of the heights and are connected by substantially vertical portions. This arrangement places an equal amount of metal above 15 and below the horizontal center line of the roof and thus locates the neutral axis along said line, thereby enabling the maximum strength of the metal employed to be utilized. This permits lighter gage sheets 20 to be used; and at the same time, results in a strong and rigid roof of simple construction, which can be cheaply manufactured and easily applied. The inverted channels or ribs 31 constitute outside car 25 lines, and the merging of the carlines into the lower plane at the eaves results in a maximum eaves clearance and greatly strengthens the roof against horizontal stresses at this point.

In Figs. 9 and 10, the sheets 25^a are similar to those shown in Figs. 1 to 8, except that the ribs or inverted channels 31^a of the sheets increase uniformly in width from the ridge toward the eaves, and there 35 is also a corresponding decrease in the height of the ribs 31^a from the ridge toward the eaves. This arrangement results in a rib of high narrow section at the ridge adapted to stiffen the roof against vertical 40 roof loads, and also results in a broad flat section of the eaves adapted to withstand the horizontal stresses caused by the racking and weaving of the car substructure. This uniform widening of the ribs 31^a from the 45 ridge toward the eaves as the height of the same decreases in the same direction enables the surplus metal gained by the decreased height of the channels to be used for widening the same and permits the use of the 50 sheet blank having parallel sides, thereby eliminating the expense of shearing the sheet to a special shape before pressing.

In Fig. 11 the sheets 25^b are shown in the form of separate channels which extend 55 crosswise of the car from eaves to eaves, the alternate channels are inverted and the side flanges of the inverted channels lap the side margins of the upwardly opening channels and are riveted together along the neutral 60 axis of the assembled channels. This arrangement results in a finished roof of the same cross-section as the roof shown in Figs. 1 to 8, the only difference being that the sheets shown in Fig. 11 are narrower and 65 have only one channel formed therein and

that twice as many rows of rivets are required.

In Fig. 12, the sheets 25^c are shown provided at their middle portions with upwardly opening channels 32^c and have flanges 50^c 70 projecting outwardly from the upper edges of the side flanges of the channels, the outer marginal portions of the flanges being lapped and riveted together. This arrangement results in a roof which is similar in 75 cross-section to the roof shown in the Fig. 11.

In Fig. 13 the roof sheets 25^d are similar to the roof sheets shown in Fig. 12, except that the sheets are twice as wide and have a 80 flat topped middle rib 31^d disposed between two channels 32^d whose outer flanges are turned outwardly as at 50^a in the plane of the top of the middle rib and lapped and 85 riveted together.

In Fig. 14 the sheets 25^e are of channel-shaped section, every other one of the sheets is inverted and their side flanges are bent outwardly midway between the upper and lower planes of the roof, forming 90 flanges 50^b, which are lapped and riveted together.

In Fig. 15 the sheets 25^f are similar to those shown in Fig. 14 except that in Fig. 15 the sheets are twice as wide as those 95 shown in Fig. 14 and are provided at their middle portions with flat topped ribs 31^f of a depth equal to twice that of the shallow channels 32^f on opposite sides thereof. The outer side flanges of the shallow channel 100 are turned outwardly midway between the upper and lower planes of the roof in the form of flanges 50^c which are lapped and riveted together.

In Fig. 16 the sheets 25^g are similar to 105 the sheets 25, except that depending outer flanges 29^g of the ribs 31^g and the upstanding flanges 30^g of the channel 32^g are bent outwardly midway between the top of the ribs and bottoms of the channels, forming 110 flanges 50^d, which are lapped and riveted together.

The hereinbefore described construction permits of considerable modification without departing from the invention, therefore, I do not wish to be limited to the exact 115 details shown and described.

What I claim is:

1. A single course metal car roof whose longitudinal section comprises straight portions at one elevation alternating with straight portions at a lower elevation and connected by substantially vertical web portions, said roof consisting of load sustaining sheets that have substantially vertical flanges at their side margins that are rigidly secured together. 120

2. A single course car roof whose longitudinal section comprises straight portions at one elevation alternating with straight 125

portions at a lower elevation and connected by substantially vertical portions, the cross-sectional area of the upper portions being substantially equal to the cross-sectional area of said lower portions, said roof consisting of load sustaining sheets that have substantially vertical flanges at their side margins that are rigidly secured together.

3. A metal car roof comprising an open-work frame and metal roof sheets supported thereon and spanning spaces therein, said sheets being positively attached together along their side margins to constitute a single course roof, said roof having alternating flat topped ribs and flat bottomed channels of equal cross-sectional area thereby securing an even distribution of the metal above and below the neutral axis of the roof whereby the maximum strength of the metal is obtained for carrying the roof load.

4. A metal car roof having alternating flat topped ribs and flat bottomed channels of equal area formed therein, extending crosswise of the car and means for securing same in position, thereby placing the neutral axis of the roof midway between the tops of said ribs and the bottoms of said channels whereby an even distribution of the metal is secured above and below the neutral axis of the roof and the maximum strength of the metal is obtained, said ribs merging into the plane of the bottoms of the channels near the eaves of the roof.

5. A single course car roof comprising a plurality of metal roof sheets that have substantially vertical flanges along their side margins and are rigidly secured together through said flanges, said roof having flat topped raised portions alternating with flat bottomed depressed portions of equal cross-sectional area, thereby securing an even distribution of metal above and below the neutral axis of the roof and enabling the maximum strength of the metal to be utilized.

6. A car roof comprising a plurality of metal roof sheets having flat topped raised portions alternating with flat bottomed depressed portions of equal area, thereby securing an even distribution of metal above and below the neutral axis of the rib and enabling the maximum strength of the metal to be utilized, the margins of adjacent sheets being rigidly secured together along the neutral axis of the roof.

7. A car roof comprising a plurality of metal roof sheets having raised flat topped portions alternating with depressed flat bottomed portions of equal area, whereby the neutral axis of the sheets is located midway between the tops of said ribs and the bottoms of said channels and an even distribution of the metal above and below said neutral axis is secured thereby enabling the maximum strength of the metal to be utilized.

ized, the raised and depressed portions of said sheets extending crosswise of the car and the side margins of adjacent sheets being rigidly secured together along the neutral axis thereof.

8. A car roof comprising a plurality of metal roof sheets extending crosswise of the car from eaves to eaves and having raised flat topped portions alternating with depressed flat bottomed portions of equal area, whereby the neutral axis of the sheets is located midway between the tops of said ribs and the bottoms of said channels and an even distribution of the metal above and below said neutral axis is secured, thereby enabling the maximum of strength of the metal to be utilized, the raised and depressed portions of said sheets extending crosswise of the car and the side margins of adjacent sheets being rigidly secured together along the neutral axis thereof, the raised portions of said sheets merging into the plane of the depressed portions thereof near the eaves, said sheets being rigidly secured to the roof substructure near the eaves.

9. A car roof comprising a plurality of metal roof sheets arranged crosswise of the car and extending from eaves to eaves, said sheets having downwardly and upwardly opening channels of equal area formed therein which extend crosswise of the car and alternate one with the other, said sheets being rigidly secured to the car at the eaves and being rigidly secured together on a line midway between the tops and bottoms of said downwardly and upwardly opening channels, which line forms the neutral axis of the sheets.

10. A car roof comprising an openwork frame, a plurality of metal roof sheets arranged transversely of the car and spanning the car from eaves to eaves, each of said sheets having an upwardly extending flange along one side margin and a downwardly extending flange along the opposite side margin and having an offset near the middle thereof, thus forming channels therein, one opening upwardly and the other opening downwardly, the depending outer flange of the downwardly opening channel of a sheetlapping the upstanding flange of the upwardly opening channel of the next adjacent sheet, said flanges being rigidly secured together.

11. A car roof comprising a plurality of roof sheets arranged transversely of the car and spanning the same from eaves to eaves, and having substantially vertical flanges at their side margins; each of said sheets having two channels formed therein of a width equal to one-half of the width of a sheet, one of said channels opening upwardly and the other of said channels opening downwardly, the web portion of said chan-

nels being connected along the middle portion of said sheets by a vertical web portion which forms the inner side flange of each of said channels, the outer depending flange of the downwardly opening channel of one sheetlapping the adjacent outer flange of the upwardly opening channel of the next adjacent sheet and being rigidly secured together flatwise through their vertical portions.

12. A car roof comprising spaced parallel side plates, a plurality of metal roof sheets arranged transversely of the car and spanning the car from eaves to eaves with their eaves ends resting on said side plates and

rigidly secured thereto, each of said sheets having an upwardly opening channel formed in one side margin and a downwardly opening channel formed in the opposite side margin, said sheets being arranged with the outer depending flange of the downwardly opening channel of one sheetlapping the upstanding flange of the upwardly opening channel of the next adjacent sheet, said flanges being rigidly secured together throughout their length.

Signed at Parnassus, Pa., this 14th day of September, 1920.

CHARLES DAVID BONSALL.
